UNITED STATES PATENT OFFICE.

ANDREW MEILLAND, OF BUFFALO, NEW YORK.

LIFE-PRESERVING SUIT.

Original application filed October 13, 1924, Serial No. 743,408. Divided and this application filed February 4, 1925. Serial No. 6,827.

To all whom it may concern:

Be it known that I, ANDREW MEILLAND, a citizen of the Republic of Switzerland, residing at Buffalo, in the county of Erie and State of New York, have invented new and useful Improvements in Life-Preserving Suits, of which the following is a specification.

In common with the invention constituting the subject of my application filed October 13, 1924, Serial No. 743,408, of which this application is a division, the general object of my present invention is the provision of a bathing suit which under normal conditions presents the usual appearance of a bathing suit, but which in the event of an emergency may be inflated so as to adequately support the wearer of the suit in the water.

Another object of the invention is the provision of efficient means for effecting inflation of the bathing suit when it is desired to impart a buoyant quality thereto.

Another object is the provision of an equipment whereby the suit may be inflated either by fluid under pressure from a tank or by the lung-power of the wearer, at the election of the wearer, or by both as circumstances demand.

Other objects and practical advantages of the invention will be fully understood from the following description and claims when the same are read in connection with the drawings forming part of this application, in which:

Figure 1 is a view showing my embodiment in use and also showing the manner in which the wearer of the suit inflates the same by lung power.

Figures 2 and 3 are views showing different positions in which the expansible fluid-pressure container may be arranged in the bathing suit.

Figure 4 is an enlarged vertical section showing the fluid pressure container deflated, and the inflating means hidden from view.

Figure 5 is a similar view showing said container inflated, and the inflating means exposed.

Figure 6 is an enlarged detail section showing the reservoir tank for the fluid under pressure and the valved conduit means in connection therewith, the valve operating bail being shown by dotted lines in open position.

Figure 7 is an edge elevation of said reservoir tank taken at right angles to Figure 6, and with the bail secured in closed position.

Figures 8, 9 and 10 are enlarged detail views illustrative of the peculiar and advantageous valve mechanism hereinafter referred to.

Referring by numerals to Figures 1, 4 and 5, 1 designates a bathing suit which may be and preferably is of the well known construction save in the respects hereinafter noted, and therefore of the same general appearance as an ordinary bathing suit.

In the embodiment shown in Figures 1, 4 and 5, the bathing suit is provided about the waist with a pocket 2 formed by inner and outer layers 3 and 4, preferably of the same material as the remainder of the bathing suit.

In the embodiment shown in Figure 2, the pocket 2^a similar to the pocket 2 is shown as located above the hip portion of the bathing suit, while in Figure 3, a pocket 2^b similar to the pocket 2 is arranged about the torso portion of the bathing suit—i. e., from about the height of the arm holes 5 to a point above the hips.

Irrespective of the location of the said body encircling pocket of the bathing suit, the pocket encloses two subcompartments 6 and 7 equipped with closure flaps 8 designed to be detachably secured in closed position by male and female fasteners 9 or other appropriate means, Figure 4.

In the body encircling pocket of the suit is arranged an inflatable container 10 of rubber or other appropriate material, the said container 10 being preferably provided at 11, Figure 4, with a comparatively thin wall portion to facilitate its inflation. When deflated, the container 10 appears as shown in Figure 4 and consequently it will not in any material degree change the appearance of

the bathing suit. When, however, the container 10 is supplied with fluid under pressure and the said fluid under pressure is retained in the container 10, the container 10 will be maintained in the distended state shown in Figure 5 and hence will form an efficient life belt possessed of sufficient buoyancy to support the body of a person in the water.

- 10 My invention contemplates the wearing of
the bathing suit under normal conditions in
or out of the water when the container 10
is in the state shown in Figure 4, and it will
be appreciated that when the bathing suit is
15 so worn it may be used in lieu of underwear.

When it is desired to impart a life saving quality to the bathing suit, the same is accomplished by supplying fluid under pressure to the container 10 and inflating the 20 said container to the extent desired or necessary. The expansion of the container 10 may be effected by lung power of the wearer through the medium of a tube 12 or by fluid under pressure through the medium of a

- 25 tube 13 in connection with a reservoir tank 14. The tube 12 is connected at one end to a nipple 15 in connection with the interior of the container 10 and provided with an outwardly seated non-return valve (not shown). Said tube 12 is also, by preference, provided with a mouth piece 17 on which are hinged valve members 18 as fully disclosed in my contemporary application, Serial No. 743,408. The purpose of the construction just described will be understood when it is stated that when the wearer of the suit desires to inflate the container 10, it is simply necessary for the wearer to open the sub-compartment 6 and remove the tube 12 therefrom and place the mouth piece 17 in his mouth with the teeth operating against the valve members 18 to open the said valve members. Then by blowing through the tube 12 the wearer is enabled to expand the container 10 until it is possessed of sufficient buoyancy to support the body of the wearer in the water. With this done, the mouth piece 17 is removed from the mouth, when the members 18 will automatically close the outer end of the tube 12 so as to exclude water from the interior thereof. The tube 12 is then replaced in its sub-compartment 6 and the said compartment is closed and fastened.

55 Removably arranged in the sub-compartment 7 of the suit is the reservoir 14 which is preferably of steel and is preferably shaped as shown in Figures 6 and 7, and is designed to contain any appropriate fluid
60 under high pressure. The said tank 14 is connected by the flexible tube 13 with the interior of the container 10. It will also be noted that the tank 14 is provided with a spring keeper 31. This keeper 31 is designed when the tank 14 is not in use to

receive a bail 32 which is designed and adapted to be snapped into and out of engagement with the keeper 31. The tank 14 also is equipped with a peculiar and advantageous valve mechanism which is clearly illustrated in Figure 8. 70

The said valve mechanism will be readily understood when it is stated that the bail 32 is provided with inwardly extending journal portions 33 with angular ends 34 on which are fixed by screws 35 cranks 36, Figures 8 and 10. Also when it is stated that the journals 33 are disposed in bearing sleeves 37 on a housing 38. The said housing 38 is apertured at 39 and is threaded at 40 on a tubular nipple 41 which, in turn, is threaded in the wall of the tank 14 as designated by 42. Packing may be and preferably is employed at the points 43, 44 and 45. Movable rectilinearly through the aperture 39 in the housing 38 and also through the tubular nipple 41 is a tube 46 to which the tube 13 is directly connected in the manner shown at the right of Figure 8 or in any other approved manner. Appropriately fixed on the tube 46 is a collar 47, Figures 8 and 9 in which are bearings 48 for the reception of the cranks 36. By virtue of this construction it will be readily understood that when the bail 32 is swung to the dotted line position shown in Figure 6, the tube 46 will be moved rectilinearly outward, while when the bail 32 is swung to the full line position shown in Figures 6 and 7 the tube 46 will be moved rectilinearly inward. Fixedly connected to the inner end of the tubular nipple 41 is a cage or open frame 49 having an interior abutment 50, and movable in the said cage or open frame 49 is a valve body 51, provided with a stem 52 and appropriately packed as designated by 53. It will be readily noted that the packed portion of the valve body 51 is opposed to the inner end of the tube 46, and therefore when the parts are positioned as shown by full lines in Figure 6 and as shown in Figure 8, the fluid under pressure in the tank 14 by exerting pressure against the valve body 51 will hold the said body 51 under pressure against the inner end of the tube 46 so that leakage of fluid under pressure from the interior of the tank 14 will be precluded. When, however, the bail 32 is sprung out of engagement with the keeper 31 and is moved to the dotted line position shown in Figure 6, the tube 46 will be moved rectilinearly outward, and the valve body 51 will follow the tube 46 in the outward movements of said tube 46 until the valve body 51 brings up against the abutment 50 whereupon the valve body 51 will be held against further outward movement, and the inner end of the tube 46 will be separated from the packed portion of the valve body 51 so that fluid under pres-

sure will be free to pass from the interior of the tank 14 through the tube 46 and the tube 13 into the container 10 for the inflation of the latter. Manifestly when the 5 container 10 is sufficiently inflated, the inflation operation may be quickly and easily stopped by the wearer swinging the bail 32 to the full line position shown in Figure 6 and snapping said bail into engagement 10 with the keeper 31. In this connection it will be understood that the last-named movement of the bail 32 will be attended by inward movement of the tube 46 until the inner end of said tube 46 moves the valve 15 body 51 inwardly away from the abutment 50 whereupon the remaining pressure in the tank 14 will operate to tightly hold the valve body 51 against the inner end of the tube 46 for the purpose before stated.

20 The bearings 48 are preferably provided with gates 48^a, Figure 9, to facilitate the assembly of the parts.

The outer end of the nipple 41 is angular for the application of a wrench when it is 25 desired to screw said nipple in or out of the wall of the tank 14.

It will be understood that in addition to the practical advantages ascribed to my improvement, the improvement is simple and 30 inexpensive in construction and is free of delicate parts such as are likely to get out of order after a short period of use.

I have specifically described the preferred embodiment of my invention, in order to implant 35 an exact understanding of said embodiment. I do not desire, however, to be understood as confining myself to the specific disclosure herein, my invention being defined by my appended claims within the 40 scope of which structural changes may be made without affecting my invention.

Having described my invention, what I claim and desire to secure by Letters-Patent, is:—

45 1. A life preserving suit having a pocket adapted to encircle the body of a wearer, an annular inflatable container for fluid under pressure disposed in said pocket, means removably arranged within the same pocket 50 for inflating said container, and means detachably secured in closed state enclosing said inflating means in the pocket.

2. A life preserving suit having a pocket adapted to encircle the body of a wearer, an 55 annular inflatable container for fluid under pressure disposed in said pocket, means removably arranged within the pocket for inflating said container, means detachably secured in closed state enclosing said inflating 60 means, the said inflating means comprising a tube connected to the inflatable container and having a nonreturn valve at its inner end and a projection controlled valve at its outer end, a tank connected to the inflatable 65 container and having a keeper, a bail piv-

oted to said tank and adapted to be snapped into and out of engagement with said keeper, and valve means controlled by said bail and adapted when the bail is snapped out of said keeper to establish communication between the tank and the inflatable container. 70

3. In life preserving means, an inflatable container, a tank, a conduit between the tank and container, a keeper on the tank, a handle arranged to be snapped into and out of engagement with said keeper, and valve means controlling said conduit and controlled, in turn, by said handle. 75

4. In life preserving means, an inflatable container, a tank having a keeper, a conduit between the tank and container, and valve means controlling said conduit and controlled by a bail arranged to be snapped into and out of said keeper. 80

5. A life preserving suit having a pocket 85 adapted to encircle the body of a wearer, an annular inflatable container for fluid under pressure disposed in said pocket, means removably arranged within the same pocket for inflating said container, a closure for the 90 pocket, and a fastener for the closure.

6. In life preserving means, an inflatable container, a tank having a keeper, a conduit between the tank and container, and valve means controlling said conduit and controlled by a bail arranged to be snapped into and out of said keeper; the said valve means being closable by pressure in the tank when the bail is closed. 95

7. A life preserving suit having an inflatable container for fluid under pressure and also having a pocket, and means removably arranged within the pocket for inflating said container, said means comprising a tank, a conduit for connecting the interior 105 of the tank and the interior of the container, valve means for controlling said conduit, and a handle for controlling said valve means, said valve means comprising a tube movable rectilinearly by the handle, a valve 110 body opposed to the tube and means for stopping outward movement of the valve body on outward movement of the tube.

8. The combination of a tank, a handle, a tube movable rectilinearly by the handle, a 115 valve body in the tank, and means in the tank for stopping outward movement of the valve body when the tube is moved outwardly.

9. The combination of a tank having a 120 keeper, a crank handle movable into and out of engagement with said keeper and connected with the tank, a tube movable rectilinearly by said crank handle, a cage arranged in the tank and receiving the inner end of the tube and having a stop, and a movable valve in the cage and opposed to the inner end of the tube and adapted on outward movement of the tube to be engaged by said stop. 125

10. The combination of a tank having a keeper, a tubular nipple secured in the tank wall, a housing connected to said nipple, a tube movable rectilinearly in the housing and nipple, a bail shaped handle having portions journaled in the housing and arranged in cranked relation to the tube, a cage ar-

ranged in the tank and connected to the inner end of the nipple and having a stop, and a valve movable in the cage and opposed to the inner end of the tube and adapted to be engaged by said stop. 10

In testimony whereof I affix my signature.
ANDREW MEILLAND.
